UNITED STATES PATENT OFFICE.

EDWARD WEISLOWITS, OF NEWARK, NEW JERSEY.

SHIPPING-JACKET.

1,136,635.

Specification of Letters Patent. Patented Apr. 20, 1915.

Application filed September 3, 1913. Serial No. 787,845.

To all whom it may concern:

Be it known that I, EDWARD WEISLOWITS, a citizen of the United States, residing at Newark, in the county of Essex and State of New Jersey, have invented new and useful Improvements in Shipping-Jackets, of which the following is a specification.

My invention consists of a new and improved shipping case or jacket to be used 10 principally for shipping oil cans, gasoline cans, etc.

Shipping jackets for cans of this kind have to be strong and durable, and the cover must be fastened on very securely so 15 as not to become loose or separated from the can in shipment. I have devised a means of securing the cover which makes it impossible for the cover to come off in shipment, and yet the cover can be easily and quickly 20 removed when it is desired to pour from the can. My improved jacket is also so constructed that the can cannot possibly slip out of the jacket when the can is tipped up to pour. I have also provided new and im- 25 proved devices for holding the can in the jacket.

In the accompanying drawings:—Figure 1 is a front elevation of the jacket showing one part of the fastening device. Fig. 2 is a sectional view of a jacket and can taken on the line 5—5 of Fig. 1. Fig. 3 is a plan view of the jacket and can in an inverted position, partly broken away to show the means for holding the can in the jacket. 35 Fig. 4 is an enlarged detail of the retaining part of the fastening device.

The device consists of a cylindrical jacket *a* made preferably of metal having several corrugations *b*. The top of the jacket is 40 bent over so as to form a ridge or collar *c* (see Figs. 2 and 4) and there is preferably a wire or strengthening member within the ridge or collar. The purpose of this collar or annular ridge is three fold. It forms a 45 base for the cover to rest on; it presses against the flange *d* of the can *e* (the can being inserted in the jacket from the bottom) and it also strengthens the body of the jacket *a*.

50 After the can *e* is placed in the jacket *a* it is securely held in position by two straps *f* made preferably of strips of resilient metal and so constructed as to lap over each other and form a joint. These straps are bolted

at *h* to the inside of the lower part of the 55 jacket *a* and while only two straps are shown, a greater number may be used if required. These straps hold the can *e* securely in position and also by reason of their resiliency tend to press the can tightly 60 against the ridge or collar *c* at the upper end of the jacket.

Around the top of the jacket is securely fastened a reinforcing strip *k* made preferably of the same kind of metal as the body 65 of the jacket *a*. This strip *k* extends above the ridge *c* and holds the cover *l* in position. If desired, the strip *k* may be secured on the inside of the jacket and the ridge or collar *c* formed on the outside on the bottom of the 70 strip *k*. When the latter mode of construction is adopted the cover *l* of course fits outside the strip *k*, and the lug member *p* is secured to the body of the case *a* instead of to the cover. At one side of the strip *k* 75 is a slot *m*. To the inside of the cover *l* is bolted a strip of metal *n* turned over at the bottom to form a hooked flange *o* which fits loosely yet securely in the opening *m*. At the opposite side of the cover is fastened 80 on the outside a strip of metal *p* bent over at *q* to form a locking member. Attached to the outside of the strip *k* is pivotally mounted a swinging catch member *r* having an opening *s* which fits over the end *q* of the 85 flange *p* where the cover *l* is held on the jacket. At each side of the opening *s*, in the member *r* are holes *t* through which may be put a wire or string *u* thus securely holding the cover in position. 90

After the can *e* is placed in the jacket *a* and the strips *f* caught together at *g*, an ordinary wooden bottom *v* may be placed in the jacket *a* and held in position by nails or screws *w*.

The upper portion of the body of the jacket *a* is provided with handles *x* swingingly mounted on the sides of the jacket.

I claim:—

In a shipping case the combination with a 100 can having a cover thereon, of a cylindrical jacket adapted to receive the can through the bottom thereof, a rigid collar formed by bending the top of the casing over an annular wire and adapted to engage on its 105 under portion the edge of said cover, resilient strips secured at one of their ends to the wall of the jacket adjacent the bottom there-

of and having their other ends extending into said jacket, said strips having means at their inner ends whereby the same are adapted to interlock and to press against said can to hold the cover against said collar, and a removable bottom for closing the bottom of the jacket.

In testimony whereof I have hereunto set my hand in the presence of two subscribing witnesses.

EDWARD WEISLOWITS.
